UNITED STATES PATENT OFFICE.

JOHN M. DOEHRER, OF BRIDGEPORT, CONNECTICUT.

SELF-HEATING SAD-IRON.

SPECIFICATION forming part of Letters Patent No. 546,656, dated September 24, 1895.

Application filed June 17, 1895. Serial No. 552,932. (No model.)

To all whom it may concern:

Be it known that I, JOHN M. DOEHRER, a citizen of the United States, and a resident of Bridgeport, in the county of Fairfield and 5 State of Connecticut, have invented certain new and useful Improvements in Self-Heating Sad-Irons, of which the following is a specification.

My invention relates to an improvement in 10 self-heating sad-irons; and the invention consists in the details of construction set forth in the following specification and claims.

To enable others to understand my invention, reference is had to the accompanying 15 drawings, in which—

Figure 1 represents a side elevation of my improved iron closed and ready for use. Fig. 2 is a central-sectional view of the burner and the rear supporting-standard for the handle-reservoir, which latter is shown broken. Fig. 3 is a side elevation of the iron with the handle and cover thrown back. Fig. 4 is a detail perspective view of the perforated shield placed within the body of the iron and partially surrounding the torch or burner, so as to prevent the flame therefrom passing through the large holes in the sides of the iron-body. Fig. 5 is a detail perspective view of the flame-spreader and perforated air-shield to protect 30 the flame when the iron is in operation.

Its construction and operation are as follows: 1 represents the iron-body, which is, of course, hollow, and the sides pierced with the large holes 1^a for the admission of air to the 35 interior of the iron. 2 is the handle, which, as shown at Fig. 2, has the hollow interior 2^a, which serves the purpose of a reservoir. The thumb-screw 3 is removed for the purpose of filling the reservoir and is firmly seated in 40 such handle, so as to effectually prevent evaporation.

The rear standard 4 is integrally formed with the reservoir-handle (see Fig. 2) and has the passage-way 4^a, leading from such reservoir to the chamber 5, which chamber is packed full of cotton waste 6 or other like material that will check the flow of the liquid, permitting nothing but the vapor to pass through to the small outlet 7 in the forward 45 end of said chamber, through which outlet the vapor passes, and at which point it is ignited,

the pointed valve-screw 4^b regulating the flow of such liquid.

8 (see Figs. 2, 3, and 5) is a sleeve which is removably attached to the reduced portion 9 55 of the packing-chamber, the forward portion of the said sleeve terminating in the inclined spreader 8^a, having the rearwardly-extending wings 8^b, which wings are angular formation direct the flame against the bottom 1^b of the 6^c iron. 10 is a perforated tongue placed between the spreader and the gas-outlet 7, and projects beyond said outlet, as shown. This tongue will admit sufficient air through the perforations 10^a for combustion, but will prevent a flow sufficient to extinguish the flame 65 when the iron is being manipulated backward and forward during the operation of ironing.

11, Fig. 2, is an annular cup-like depression 7^c or recess at the base of the burner to hold sufficient liquid, which, as a preliminary step in starting the flame, is first ignited, so as to warm up the surrounding metal and chamber and convert the vapor into gas. 75

12 is a cover formed integral with the two supports 4 and 13, and overlying this cover is the thin metal shield 14 to protect the operator's hand from the direct heat of the iron. The whole upper part of the iron is pivotally 80 supported upon the pin 15, passing through the rear of the iron-body. The handle portion of the iron is locked to the body by means of the turn-bolt 16, whose lower projection 16^a is adapted to engage with the ledge 1^c of 85 the iron-body 1.

17, Figs. 1, 3, and 4, is a perforated sheet-metal shield bent in the form shown more fully at Fig. 4. This shield is placed within the hollow iron-body 1 and will rest on the 90 bottom thereof, so that the two sides and end of such shield are interposed between the burner and sides and front end of the iron. This shield will cut off the flame, so that it cannot pass through the holes 1^a of the iron 95 when said iron is being rapidly manipulated back and forth during the operation of ironing. It is immaterial, however, whether the shield comes in contact with the inner walls of the sad-iron or is placed a short distance 100 therefrom, the result being the same in either case.

To operate the iron, the reservoir is first filled by removing the plug 3. Then by means of the valve-screw 4^b sufficient liquid, which may be either naphtha, gasoline, or other like volatile fluid, is allowed to flow through the channel-way 4^a to the packing-chamber 5. Then the cover is tipped back into a vertical position, and a small quantity is then poured into the annular depression or recess 11. This recess will hold a sufficient quantity of the liquid so that, when ignited, it will burn long enough to heat the surrounding metal sufficient to vaporize the fluid and cause the vapor escaping through the small outlet 7 also to ignite, whereupon the cover is closed and fastened and the iron is soon heated sufficient for use, the spreader 8^a serving, as before mentioned, to direct the flame toward the bottom of the iron, the reservoir 2 being capable of holding sufficient liquid to last for several hours. If, however, it should become necessary to fill the reservoir before the ironing is completed, the flame is extinguished and the reservoir refilled, in which case it will not be necessary to put any fluid in the annular recess 11, as there will be heat enough already developed, so that the flame may be started by the application of a match at the outlet 7.

Having thus described my invention, what I claim as new, and desire to secure by Letters Patent, is—

1. The improvement in sad irons of the

character described, comprising in combination, the liquid reservoir handle 2 and means 35 for filling the same; standard 4 having a passageway therethrough for the liquid and a regulating valve screw therefor; said passageway terminating at a chamber filled with packing having an outlet for the vapor and at 40 which point it is ignited, combined with a downwardly projecting spreader to direct the flame against the bottom of the sad iron; a perforated shield within said spreader to break the force of air and thus protect the 45 flame; the hollow sad iron to which the handle portion is pivoted; holes in the sides of said iron for the admission of air; a cover for said iron integral with rear standard; and means for locking the cover to the iron, as 50 set forth.

2. In a sad iron of the character described, comprising in combination the handle reservoir hinged to the hollow sad iron; cover therefor; burner, spreader, and perforated flame 55 protector, as shown; and a perforated shield within the iron to prevent the flame passing through the air holes in the sides of said iron, all as described and for the purpose set forth.

Signed at Bridgeport, in the county of Fairfield and State of Connecticut, this 11th day of June, A. D. 1895.

JOHN M. DOEIRER.
